UNITED STATES PATENT OFFICE

130,876

DESIGN FOR A LEMON JUICE DISPENSER

Edith Sarah Reid, Kansas City, Mo.

Application March 31, 1941, Serial No. 100,040

Term of patent 7 years

To all whom it may concern:

Be it known that I, Edith Sarah Reid, a citizen of the United States, residing at Kansas City, in the county of Jackson and State of Missouri, have invented a new, original, and ornamental Design for a Lemon Juice Dispenser, of which the following is a specification, reference being had to the accompanying drawing, forming a part thereof.

Fig. 1 is a perspective view of a lemon juice dispenser showing my design.

Fig. 2 is an end elevational view thereof.

Fig. 3 is a bottom plan view of the dispenser.

I claim:

The ornamental design for a lemon juice dispenser, as shown.

EDITH SARAH REID.
